CLAIM

I claim the ornamental design for a lead acid battery cover lid, as shown and described.

DESCRIPTION

FIG. 1 is a perspective view of a lead acid battery cover lid showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a perspective view thereof showing the lead acid battery cover lid in use;

FIG. 8 is a perspective view thereof showing the lead acid battery cover lid in use, in an alternate configuration; and,

FIG. 9 is a perspective view thereof showing the lead acid battery cover lid in use, in a second alternate configuration. The features shown in broken lines depict environmental structure only and form no part of the claimed design.
